ATTORNEY.

UNITED STATES PATENT OFFICE

125,659

DESIGN FOR A MANIKIN

Kathryn Fox, Chicago, Ill.

Application October 17, 1940, Serial No. 95,887

Term of patent 3½ years

To all whom it may concern:

Be it known that I, Kathryn Fox, a citizen of the United States, residing at Chicago, in the county of Cook and State of Illinois, have invented a new, original, and ornamental Design for a Manikin, of which the following is a specification, reference being had to the accompanying drawing, forming a part thereof;

Fig. 1 is a front perspective view of the manikin, showing my design; and
Fig. 2 is a side perspective view.

I claim:

The ornamental design for a manikin, as shown.

KATHRYN FOX.
